Marquis H. Lockwood

UNITED STATES PATENT OFFICE

MARQUIS H. LOCKWOOD, OF NEW YORK, N. Y., ASSIGNEE TO CHARLES ERRETT, OF NEW YORK, N. Y.

COLLAPSIBLE PAPER CUP

Application filed June 2, 1923, Serial No. 642,898. Renewed April 3, 1929.

My invention relates more particularly to a collapsible paper cup provided with a bottom of flexible or pliable material secured thereto, the bottom being so formed and secured to the walls of the cup that the latter will fold perfectly flat, and yet when fully open or distended, it will be substantially cylindrical in cross section.

Flat cups of the envelope type are well known and are sold and used in large quantities, but this form of cup is objectionable, in that, when filled and in use, it cannot be set down, but must be held in the hand or otherwise supported. Various attempts have been made to overcome this objection, by the construction of foldable paper cups, having square or rectangular bottoms and folded substantially similar to a paper bag, but this type of cup is more or less clumsy to handle and does not present the neat appearance of a round cylindrical or frusto-conical cup.

The object of my improvement is to provide a folding or collapsible cup, which when distended, will be capable of assuming a cylindrical or frusto-conical shape, substantially circular in cross section from the top to the bottom thereof. This is preferably accomplished by forming the walls of the cup from a single blank of paper of suitable weight or thickness to give the necessary rigidity to the body of the cup and attach thereto a bottom of comparatively thin flexible material so shaped and folded as to completely seal the bottom and collapse with the walls of the cup into flat form.

A further object is to so fold the flexible bottom that it may be secured to the blank forming the walls of the cup, while in collapsed condition, thereby facilitating manufacturing the cups at low cost. It will be understood, however, that a flexible bottom adapted to be collapsed in the manner described, may be secured to the walls of the cup in any suitable manner, and so arranged that it may fold or collapse when the walls of the cup are collapsed into flat form.

In the accompanying drawings, I have shown one form of my improved collapsible paper cup, which when fully distended, is frusto-conical in shape. Fig. 1 shows the cup

completely collapsed with the bottom section indicated by dotted lines; Fig. 2 represents a view looking downward into the cup when the latter is partially open; Fig. 3 is a vertical section of the fully distended cup, the section being on the line 3-3 of Fig. 4; Fig. 4 is a transverse vertical section of the cup fully distended, the section being on the line 4-4 of Fig. 3; Fig. 5 is a plan view of the blank for forming the walls of the cup, the bottom section being located thereon prior to folding over the ends of the wall blank; Fig. 6 is a plan view of the blank for the bottom with fold lines indicated by dotted lines, and Fig. 7 is a view of the bottom blank partially folded.

Referring to the drawings, it will be seen that my improved cup comprises a blank 1, adapted to form the walls of the cup, the wall blank in the present case being so shaped that when distended it will form a frusto-conical cup. The wall blank 1 forming the body portion of the cup may be made of any suitable material, but is preferably blanked out of paper of sufficient weight and thickness to give the necessary body and stability to the cup, and may be water proofed or at least of close pressed material so as to be capable of resisting moisture for a limited period of time. The cup blank 1 is adapted to be folded upon itself along the dotted lines 2 and 3 of Fig. 5. The ends of the blank, in completing the cup, are adapted to overlap and may be secured together by any suitable cement, the amount of overlap, covered with cement, being indicated at 4 in Fig. 5. The bottom 5 is preferably formed from a blank of thin flexible or pliable paper, cloth or other suitable impervious material, and may be folded in any suitable manner to provide a foldable bottom for the cup. The flexible bottom may be collapsed into flat form at the time it is secured to the walls of the cup or secured thereto and folded or flattened by flattening the walls. In the present instance, the blank for the bottom is preferably shaped substantially as shown in Fig. 6 of the drawings, and adapted to be folded on the dotted lines. Lengthwise, the bottom blank is folded with what I term a saddle fold along the

160

line 6, (see Fig. 7) the edges of the blank being folded upward along the lines 7, thus forming an inverted fold at 8, at each end of the downward fold on the line 6, substantially as indicated in Figs. 5 and 7 of the drawings. The upwardly folded edges of the blank form flanges 9, extending angularly with respect to the saddle fold and, as indicated in Figs. 1 and 7, the points of intersection of the flanges on each side of the saddle fold are folded up against the flanges 9 along the lines 10, thereby forming triangular tabs 11 which may be cemented to the folds of the flanges 9, if desired or found necessary, to make the joint tight. Therefore, a saddle fold bottom, when the cup is flat, has infolded triangular portions which, when the cup is opened, form V-shaped portions, joining the end walls to the opened bottom of the cup. (See Fig. 4.)

When the flexible bottom section is folded as described, it will be thin and flat and, as shown in Fig. 5 of the drawings, the flanges 9 and tabs 11 may then be covered with suitable cement, (indicated by stippling in Fig. 5). The folded bottom blank is then laid upon the wall blank 1, between the lines 2 and 3 and attached thereto, the reverse folds at 8 extending along the folding lines 2 and 3. With the folded bottom laid upon and attached to the wall blank, as shown in Fig. 5, and the exposed flanges 9 and tab 11 covered with cement, the ends of the blank 1 may be folded over the bottom section and secured thereto, and the overlapping ends of the blank 1 may be secured together by cement on the portion 4, as indicated in Fig. 5 of the drawings. The cup is thus completed in flattened form and will have substantially the shape and appearance shown in Fig. 1 of the drawings.

It has been found in practice that after the cup is completed in the flat, it can be readily opened by pressing on the edges of the flat cup at the points 8. The compression along the saddle fold will be such as to force the flat walls of the cup outward, and open the cup, which when fully distended, will be frusto-conical in shape and substantially circular in cross-section from top to bottom. The cup is shown in Fig. 2 with the top partially open, disclosing the bottom section before it is completely distended. When the cup is fully opened and filled with liquid, the pressure of the liquid will naturally tend to cause the cup to assume a substantially circular cross section. The bottom being flexible, it will offer little or no resistance to the pressure of the contents of the cup and hence the cup at the bottom will also become substantially circular in cross section. It will be understood that it is practically impossible to flatten a round body provided with a round bottom, for the bottom cannot be extended as the walls are forced together. Therefore, in my improved cup, it will be seen that the flexible

bottom blank 5 is longer in one direction than in the other and is provided with the saddle fold in the long direction. The folds of the bottom are so arranged that when distended, the bottom would normally be square, as indicated by the dotted lines 10 intersected by the lines 12 at right angles thereto, as shown in Fig. 6 of the drawings, but when filled with liquid the flexible bottom will tend to assume the round form, limited by the heavier cup walls. It will be readily understood the long saddle fold allows the bottom to extend laterally when the walls of the cup are flattened, the amount of extension being equal to the line 6 of the saddle fold between the inverted folds 8, which is one half the circumference of the distended cup at these points.

In manufacturing my folded or collapsible cup, it will be understood that the bottom may be inserted and attached to the walls of the cup in any suitable manner, but since such cups are intended to be sold and shipped flat, it is preferable to manufacture them in that way. In forming the bottom section, the various lines of fold may be impressed thereon by scoring with a suitable die, if it is found desirable to do so, but this is not necessary, for I have found in practice that the bottom can be readily folded and the cup assembled as described, and when the flat cup is pressed on the edges thereof, the cup will readily open. When so opened, the cup will set on its own bottom and present the appearance of an ordinary, round frusto-conical paper cup.

My improved collapsible cup is so designed that it may be readily manufactured by special automatic machinery, and this is facilitated by the readiness with which the cup can be assembled in flat form. In manufacturing, the blanks for forming the frusto-conical walls of the cup are cut or punched and placed singly on a folding plate or table. The bottom blanks are punched from suitable material and, by means of suitable folding mechanism, are folded into thin flattened form, ready for assembly with the wall blank. The over-turned flanges 9 and tab 11 are then covered with paste, glue or a suitable water proof cement and the folded bottom laid on the wall blank 1, in the position shown in Fig. 5 of the drawings. The edge 4 of the wall blank is covered with cement and the blank 1 is then folded along the lines 2 and 3 to enclose the bottom section, the whole being pressed together, thus completing the cup in flattened form.

While I have shown a cup which, when fully distended, will be frusto-conical, it will be understood that the angle of the walls may be varied so that the cup may be of any desired shape from widely flaring to substantially cylindrical. It will also be understood that I have shown only, what is not considered, the preferred form or method for folding the bottom section, but obviously, the

bottom section may be folded in various other ways to obtain the desired surplus material required to permit the flat folding of the cup, and also to permit the completion of the cup in its flattened form.

5 It is believed that my improved cup with an attached flexible bottom, which permits the cup to be collapsed or folded into flat form is particularly novel, and, therefore, I do not 10 wish to be limited to the specific form shown and described nor to any particular method of making the cup, for it will be understood that various modifications may be made in the shape and dimensions of the elements for 15 forming the cup, and particularly in the shape and folding of the bottom section and the method of attaching the same and various other modifications in the details of construction may be made without departing 20 from the spirit and scope of the invention.

I claim:—

1. In a cup of the character described, the combination of a collapsible blank forming the walls of the cup having but two diametrically opposite fold lines, and a separate blank secured thereto forming the bottom of said cup and provided with fold lines for a saddle fold, the bottom and wall blanks being adapted to fold on their respective fold lines so 30 that the cup may be collapsed into flat form, with the bottom in a saddle fold between single thickness flat walls of said wall blank.

2. In a cup of the character described, the combination of a blank folded with a saddle fold to form the collapsed bottom of the cup, a blank having its ends secured together and folded in single folds at the ends of said saddle fold to form the collapsed walls of said cup, and means for securing said blanks 45 together in water tight relation.

3. A collapsible cup of the character described, comprising a blank of material adapted to form the walls of the cup, the ends of said blank being folded by opposite single 50 folds into overlapping relation and secured together to form single thickness walls of the cup in flat form, and a bottom folded in a collapsed saddle fold inserted between and secured to said walls, said cup being distended or opened by pressure on the opposite fold edges of said walls.

4. The method of forming a collapsible paper cup, which comprises folding a blank to form a flat collapsed saddle fold bottom, 55 then securing one side of said flat folded bottom to the inside of a wall blank, then folding said wall blank over said bottom and securing the same to the other side of said bottom to form single thickness flat walls on each 60 side of the latter, said flat walls forming the walls of the cup when distended.

5. The method of forming a collapsible paper cup, which comprises folding a blank to form a flat collapsed saddle fold bottom, 65 securing one side of said flat folded bottom

to the inside of a wall blank, then folding said wall blank over and securing the same to the other side of said bottom, and simultaneously securing the ends of the wall blank together to thereby complete the cup in collapsed form.

6. The method of forming a collapsible paper cup, which comprises forming a flat folded collapsed saddle fold bottom by suitably folding a blank of flexible material, securing one side of said folded collapsed bottom on a blank which when folded is adapted to form a single thickness flat wall on each side of said bottom, folding the last named blank over the collapsed bottom and securing the same to the other side of said bottom and the ends of said blank together, thereby forming a collapsed flat cup capable of being distended by pressure on the fold edges.
